UNITED STATES PATENT OFFICE.

ROYAL L. BOULTER, OF LOS ANGELES, CALIFORNIA.

TELEGRAPH-KEY.

1,109,818.

Specification of Letters Patent.

Patented Sept. 8, 1914.

Application filed March 29, 1912. Serial No. 687,198.

To all whom it may concern:

Be it known that I, ROYAL L. BOULTER, a citizen of the United States, residing at Los Angeles, county of Los Angeles, and State of California, have invented certain new and useful Improvements in Telegraph-Keys, of which the following is a specification.

This invention relates to telegraph keys.

The present invention relates to that class of telegraph keys known as "transmitters" or "vibrators" which employ a vibratory reed or pendulum in connection with a key for the purpose of making the dots to relieve the operator of the repeated finger and wrist movements necessary with the ordinary telegraph key when making a series of dots. This class of transmitter also employs a separate key for forming dashes. The two keys are, in most transmitters at present known to the art, arranged for movement laterally or sidewise, as contradistinguished from the up and down movement of the old type of telegraph key, and they are particularly designed for sending messages rapidly with a minimum effort on the part of the operator, but are particularly useful to operators having writer's cramp or telegrapher's paralysis.

Heretofore transmitters of this type, while superior in many respects to the old style Morse key, have been incapable of such adjustment as to adapt them for both fast and slow work and for use on both long and short lines; they have usually also been complicated and occupied considerable space, beside being liable to derangement, as well as subject to other defects.

The present invention has for its object the provision of a transmitter or vibrator telegraph key which will be simple, compact, strong, durable, susceptible of any desired adjustment of the contacts, particularly those used for making the dots, extremely sensitive to every movement of the operator's fingers, arranged for ready adjustment to suit the play of the fingers of different operators, and for adjustment of the vibrator to adapt the instrument for use in slow or fast work and on either short or long circuits. These objects I accomplish by the provision of certain new features, arrangements and combinations of parts, as will appear more fully hereinafter and be recited in the appended claims.

Among the new features constituting the

present invention are key stems arranged for lateral oscillation, finger-pieces or buttons adapted for adjustment to different heights on the key stems to suit the peculiarities of different operator's finger and wrist movements, flexible key stems which cushion the movement of the hand, a pendulum vibrator itself of new construction and having a bob or weight, an adjustable contact, and new spring means for regulating the tension, a new contact device having means whereby both coarse and fine adjustments may be had, whereby, in connection with the contact of the vibrating pendulum, the adjustment of the contacts may be changed to suit all of the varied conditions of use at different times.

In the accompanying drawings:—Figure 1 is a vertical section with certain parts in full lines; Fig. 2, a side elevation looking toward the pendulum and the contacts; Fig. 3, a front elevation looking toward the operating keys; Fig. 4, an end elevation showing the pendulum vibrator and the key for operating it; Fig. 5, a detail perspective of the pendulum vibrator and its operating key; Fig. 6, a similar view of the contact for making dashes and its operating key; Fig. 7, a detail perspective of the adjustable contact and its mounting; Fig. 8, a longitudinal section through the vibratory pendulum showing the springs in full lines; Fig. 9, a longitudinal section through the adjustable contact, certain parts being in full lines; and Fig. 10, a detail of a modified vibrator contact.

The base 1 is preferably formed integral, though not necessarily so, with the hollow frame 2 rising therefrom. Extending through a web 3 in the base 1, is an insulated stem 4 to which one of the terminals of the conductor cord 5 is connected at 6. The stem 4 is secured to the standard or frame 2 by a cross-piece 7 which is insulated at 8 from the frame and has connected thereto or formed integral therewith an arm 9 in which a contact support 10 is held by a clamping screw 11 which permits a general or coarse adjustment of the contact 12. This contact is pivoted at 13 to the upper end of the support and may be raised or lowered to effect a fine adjustment of the contact by the screw 14 whose tip bears upon the upper end of the support 15. To hold the contact 12 down and to permit it to yield, according to the ad-

justment desired and the conditions of use, there is provided a contractile spring 16 which is connected at its upper end to the contact member and extends downwardly 5 through the bore of the contact support and at its lower end is provided with a screw and nut 17. By turning the nut, the tension of the spring may be regulated and the adaptability of the contact 13 to yield may 10 be regulated.

So far as I am aware, a contact of this character has not heretofore been used on a telegraph key. It has the advantages of adaptability for a general or coarse adjustment and for a quick and easy fine adjustment to adapt it to the changing conditions of sending as met with in ordinary practice and, particularly through the use of this contact, the adaptability of the instrument 20 for use on short or long lines or in slow or rapid sending is made possible. The other terminal of the conductor cord 5 is attached to any part of the base 1 or frame 2 and to enable the circuit to be closed through the instrument, I provide a circuit closer 18 pivoted at 19, whose end is adapted to contact with a washer 20 or other part of the stem 4. Normally this circuit closer is out of contact 25 with the said washer.

30 Rockably mounted in the standard 2 is the key pivot 21 carrying a contact 22 which is adapted to be made to engage the upper part of the stem 4 but is normally kept from such engagement by a spring 23 whose 35 tension is regulated by a knurled screw 24, the play of the contact being limited within any desired bounds by a knurled set screw 25. The contact 22 forms the dashes of the alphabet.

40 Secured to and depending from the rocker pin 21 is a key stem 26 which is of flexible material and is preferably in the form of a flexible flat strip. The key or finger-piece 27 is of some suitable insulating material, 45 as usual, and has a split clamp 28 which embraces and is adapted for engagement with the key stem 26, a screw 29 serving to bind the parts of the clamp together. The key button being adjustable up and down on the 50 key stem 26, enables it to be disposed at any desired height according to the requirements of the person using the key, and the flexibility of the stem affords a sufficient cushion to the pressure of the operator's finger to 55 render sending easy.

Rockably mounted in the upright 2 is another pivot member 30 which carries a flexible depending key stem 31 similar to the key stem 26, and there is provided a key 60 button or finger-piece 32 which has a clamp 33 adjustably connecting it to the stem 31, whereby it may be adjusted vertically to suit the requirements of the operator. The stem 31, like stem 26, being flexible, the 65 movement of the operator's finger, usually

the thumb, is cushioned and sending is rendered easy.

Carried by the pivot 30 is an arm 34 which extends up through the top of the frame or standard 2 and laterally at that 70 side which carries the contact 12 heretofore described. A spring 35 and an adjustable knurled screw 36 afford means for placing any desired tension on the pendulum arm 34. Knurled set screws or stops 75 37, 37' engage the arm 34 and limit its play.

Depending from the arm 34 are the pendulum leaf springs 38 which are light and yet of sufficient rigidity to absorb unnecessary vibration and still afford suitable flexibility. These pendulum springs are connected by a cross-piece 39 from which rises a tubular member 40 disposed between the pendulum springs and on which a pendulum weight or bob 41 may be adjusted and held by a set screw 42. For slow sending, the bob will be lowered and for rapid sending, it will be raised to any desired point according to the requirements of use. Extending down through the tubular member 40 is a coil spring 43 whose lower end is made fast at 44 and whose upper end is connected by a screw and nut 45 to the pendulum arm 34, this device affording 95 means for regulating the tension on the pendulum springs 38 so that their tendency to vibrate may be regulated as may be desired. Slidable on the tubular member and adapted to be secured thereto at any desired 100 height is a collar 46 having screw 47 and provided with contact 48, which is positioned underneath the contact 12 and is adapted to engage it when the finger-piece 32 is moved.

A somewhat more sensitive contact 48 is shown in Fig. 10, the contact being carried by light or weak springs 48^a attached to collar 46 and regulated as to play by a screw 46^a. The independent yieldability of the 110 contact lengthens the time of its engaging the contact 12 without appreciably diminishing the vibrations of the vibrator and also permits adjustment for longer or shorter contact.

On the base 1 is a set screw 49 which is adapted to check the back play of the pendulum by engaging the cross-piece 39.

The contacts 12 and 48 are for making the dots of the alphabet.

The cord 5 has a jack or plug 50 which may be inserted under the contact lip of an ordinary telegraph key when it is desired to insert the present key in the circuit. The circuit may then be closed by the circuit 125 closer of the present invention.

The vibrating pendulum constitutes an important part of the present invention. I am aware that vibrating pendulums arranged vertically have heretofore been used 130

on telegraph transmitters but, so far as I am aware, they have not been operated from their point of suspension or substantially so, which, in the present invention, with the use of the springs 38, renders the pendulum extremely sensitive, but this in turn, is capable of any desired regulation by shifting the pendulum weight or bob up or down and securing it where desired and, further, the sensitiveness may be regulated as found desirable by the spring tensioning device carried by the pendulum by which the tension of the springs 38 may be changed. All of these features are new with me, so far as I am aware and, severally and jointly, they contribute to the sensitiveness and adaptability for a wide range of adjustment to suit circuits of different lengths and either fast or slow sending as well as the individual peculiarities of different operators, giving results which are not obtainable with other vibrator keys known to the art.

In operating the key, the hand is made to play in a more or less lateral direction, the forefinger being used to manipulate the key button 27 to form the dashes and the key button 32 is manipulated by the thumb to form the dots. On pressing upon the key button 32, the arm 34 is rocked and the entire pendulum moved, thus setting it in vibration and causing the contact 48 to strike the contact 12 a number of times which, in turn, is controlled by the period of time the key button 32 is held depressed. Thus, one or several dots may be automatically formed, due to the vibration of the pendulum and the operator is relieved of the tiresome repetition of dots.

Having thus described my invention, what I claim as new and desire to secure by Letters Patent, is:—

1. In a telegraph transmitter, the combination with a pivotally mounted flexible vibrator whose vibratory part projects freely, of means for vibrating said vibrator, and means carried bodily by the vibrator and its pivotal mounting adapted for changing and maintaining the tension of its freely projecting flexible part independent of the means for accomplishing its vibration.

2. In a telegraph transmitter, the combination with a pivotally mounted flexible vibrator whose vibratory part projects freely, of means for vibrating said vibrator, and

self-contained adjustable spring means carried bodily by the vibrator and its pivotal mounting adapted for changing and maintaining the tension of its freely projecting flexible part independent of the means for accomplishing its vibration.

3. A vibrator for telegraph transmitters having separated leaf or ribbon springs, cross end members connecting said springs, a member carried by the vibrator, and an adjustable weight carried by said member.

4. A vibrator for telegraph transmitters having leaf or ribbon springs, end members connecting said springs, a tubular member carried by one of said end members, a weight adjustably carried by said tubular member, a coil spring connecting the end members together, and means for adjusting the tension of said coil spring.

5. In a telegraph key, the combination with a vibrator, and a contact carried thereby, of a movably mounted contact, and means whereby said movably mounted contact may be shifted as an entire lengthwise of the vibrator to different positions to obtain a coarse adjustment and having means whereby it may be finely adjusted independently of such shifting in the same direction in which it is adapted to be shifted.

6. In a telegraph key, the combination with a hollow slidable contact support and means for securing it where adjusted, of a contact movable in relation to, and mounted on, said contact support, a spring secured to the contact and located within the hollow support and secured thereto, and an adjusting screw for adjusting the contact in relation to said support.

7. In a telegraph transmitter, the combination with a vibrator, and a contact carried thereby which is adjustable lengthwise thereof, of another shiftably mounted contact adapted to be engaged by the contact aforesaid, and independent means for adjusting said shiftably mounted contact in the direction in which it is shiftable, whereby both coarse and fine adjustments of said shiftably mounted contact may be had.

In testimony whereof, I hereunto affix my signature in presence of two witnesses.

ROYAL L. BOULTER.
